UNITED STATES PATENT OFFICE

159,455

DOOR KNOCKER

Chauncey E. Waltman, Chicago, Ill., assignor to Nutone Incorporated, Chicago, Ill., a corporation of New York

Application April 1, 1949, Serial No. 1,742

Term of patent 3½ years

(Cl. D10—7)

To all whom it may concern:

Be it known that I, Chauncey E. Waltman, a citizen of the United States, residing at Chicago, in the county of Cook and State of Illinois, have invented a new, original, and ornamental Design for a Door Knocker, of which the following is a specification, reference being had to the accompanying drawing, forming a part thereof.

I claim:

The ornamental design for a door knocker, substantially as shown.

CHAUNCEY E. WALTMAN.
